WEATHER STRIPPING

David A. Seligman, New York, N. Y.

Application May 15, 1935, Serial No. 21,490

7 Claims. (Cl. 20—69)

The present application relates to weather stripping to be utilized in and around the windows, doors and other opening closures in house-
hold or other buildings.

Among the objects of the present invention is to provide an improved inexpensive, easily applied weather stripping which may be made of stamped sheet metal and which will assure adequate protection against the ingress of weather without at the same time interfering with the operation of the window, door, or other opening closure to which it may be applied.

Another object is to provide an inexpensive, readily applied sheet metal window stripping which may be particularly applied to windows, which will assure adequate protection with varying climatic conditions from winter to summer and of different humidities, and which will not interfere with the raising or lowering of windows even after usage for a longer period of times.

Other objects are in part obvious and in part pointed out hereinafter.

In accomplishing these objects according to the embodiment of the invention, it has been found most suitable to provide angle strips, the angles of which are usually substantially less than 90°, but in any case desirably more acute than the angle of the frame to which they are applied. The ends of these angle strips may be provided with extension members or fingers to be turned over the corner of the end of the panel or frame to which they are applied to enable adjustable or fixed connection thereto.

In one form of the present invention the ends of the angle member are split so as to form two fingers at each end, which may be slotted or provided with openings to enable them with automatic adjustment to be screwed or attached to the end of the frame to which they are connected or which fingers may be fitted into suitable receptacles or receivers at the ends of the frame structure permitting such automatic adjustment.

In the drawing, Fig. 1 is a front view of the window construction with the weather stripping of the present invention attached to the sash structures.

Fig. 2 is a side view on a large scale upon the line 2—2 of Fig. 1.

Fig. 3 is a fragmentary transverse sectional view upon the line 3—3 of Fig. 1.

Fig. 4 is a bottom view illustrating how the attachment of the side weather stripping may be made to the upper or lower end of a sash.

Fig. 5 is a perspective view of the side weather

stripping of Figs. 1 to 4 foreshortened and showing the splitting of the ends thereof.

Fig. 6 is a fragmentary perspective view of a lateral weather stripping construction.

Fig. 7 is an end view of an alternative connection of the end of the weather stripping to the end of the sash.

Fig. 8 is a side sectional view upon the line 8—8 of Fig. 7.

Fig. 9 is a fragmentary view of the metal strip which may be stamped out of flat metal and bent to form the weather-stripping of Figs. 3 to 5.

Referring to the drawings, the window of Figs. 1 and 2 is provided with the frame 10 having top and bottom members 11 and 12 and side members 13.

Within the frame the side members 13 of the frame are provided with the inside and outside channels 14 and 15, respectively, in which are respectively received the lower sash 16 and the upper sash 17.

Each of the sashes 16 and 17 respectively is provided with frame structures 18 and 19 (see Fig. 2), which frame structures are provided with the upper horizontal members 20 and 21, the lower horizontal members 22 and 23, and the side members 24 and 25. Each of the sashes is provided with a glass pane, respectively, 26 and 27.

As indicated in Fig. 2, the upper window frame 11 is provided with the grooves or channels 27 and 28, the latter for receiving the sash 16 when in its uppermost position and the sill or lower frame member 12 is provided with the recess 29 for receiving the sash member 17 in its normal lowermost position and is also provided with the level sill surface 30.

The intermediate ridge 31 separates the channels 14 and 15 and the sliding sashes 16 and 17. The sashes 16 and 17, as shown in Figs. 1 and 2, abut each other to close the frame opening 10, and to open the interior of the room to the outside, the sash 16 is lowered and/or the sash 17 is raised.

The window and sash structure so far described do not form part of this invention which is primarily directed to the weather stripping associated with such sash structure.

Referring to Figs. 3 to 8, it will be noted that the particular feature of the present invention resides in having the weather stripping carried upon the sash members and not on the frame members, the weather stripping being substantially concealed within the channels 14 and 15 in which said sash members 16 and 17 slide.

It is a particular feature of the present inven-

tion that the sheet metal forming the weather stripping is so formed that it will of itself have the necessary resiliency to assure a substantial weather seal regardless of relative separation or contraction between the sash and the frame, as with varying climatic conditions or upon aging.

It is also a particular feature of the present invention that the upper and lower horizontal edges of both sash members 16 and 17 may be 10 weather-proofed in substantially the same fashion as are the side edges of the sash members 16 and 17.

Referring to the side weather-stripping 35, shown in Figs. 3 to 5 and 9, this weather-stripping 35 may be formed by stamping a sheet or strip of metal, as indicated in Fig. 9, to have the two side portions 40 and 41, which side portions may be bent in respect to each other along the dotted line 42 to form an acute angle, as best 20 indicated in Fig. 3. It will be noted that the angle between the side portions 40 and 41 is relatively so acute in respect to the right angular edge 43 of the sash 25 that contact will only be made along the edges at 44 and 45.

25 The natural resiliency of the sheet metal making up the angle 40—41 will be such as to permit separation or movement together of the sides 40—41, whereby a perfect seal will be assured across the space 46 at the side of the sash as 30 well as the space 47 at the front or rear of the sash. As the spaces 46 and/or 47 increase, the angle between the sides 40—41 of the strip will decrease, and as the spaces 46 and/or 47 increase, the sides 40—41 will be moved apart with increase 35 of the angle of the strip.

As indicated in Figs. 5 and 9, the upper edge of the strip is slit at 47 to form the fingers 48 and 49, and the lower end is similarly slit, as indicated at 50, to form the fingers 51 and 52.

40 The fingers 48 and 49 are preferably each provided with the elongated eyes 53 and 54 (see Figs. 4 and 5), which when they are bent downwardly, as indicated at the upper part of Fig. 5, register so that a single screw member or nail 55 (see Fig. 4) may be passed through the slots 53 45 and 54 into the top of the frame of the sash member, as best indicated in Fig. 4.

The lower fingers 51 and 52 may be similarly 50 constructed and attached to the sash frames 20 to 23, as indicated in Fig. 4. The grooves 53 and 54 enable the fingers 48 and 49 to move upon the post or screw 55 to enable automatic adjustment of the strip.

55 In Fig. 6 is shown one form of a top and bottom sealing strip 60 which may also be conveniently stamped out of a sheet or strip of metal and attached to the lower edges of the frames, as indicated in Figs. 1 and 2.

As indicated, the strip is provided with the vertical side 61 and the horizontal side 62, which 60 are bent in respect to each other at the line 63.

The slots 64 and 65 may receive suitable posts, screws, or nails, as indicated at 66 in Figs. 1 and 2, enabling ready attachment of the upper and lower sealing strips, and also automatic adjustment thereof.

70 These upper and lower sealing strips 60 are preferably also formed with an angle substantially more acute than the angle of the sash frame to which they are attached, so that they will expand when the sashes are moved out of their grooves or contacts with each other, as indicated in Fig. 2, and so that they will be pressed into position against the sash edges, as 75 indicated at 60 in Fig. 2, when the sashes are

respectively elevated and lowered to the closure positions.

It will therefore be noted that applicant has provided a simple, weather stripping attachment for sashes which may be directly attached to the sash and which therefore may be most inexpensively applied and is particularly readily concealed within the sash and frame construction for the most part.

The weather stripping, as indicated, may be 10 readily stamped out of sheet metal and the bending of it into desired shape automatically assures a resilient seal, when such stripping is connected to the sash structure.

It will also be noted that the slotted connection 15 of said weather stripping to the sash structure enables substantially automatic adjustment thereof to take care of opening and closing of the sashes and expansion and contraction of the sashes with varying humidity and temperature 20 conditions.

In Figs. 7 and 8 is shown an alternative method 25 of attaching the ends of the weather stripping to the sash frame to allow for automatic adjustment thereof, similarly functioning parts being indicated by the same numerals as in Figs. 1 to 5 but primed.

In Figs. 7 and 8 the top of the sash frame, as indicated at 21', is attached to the folded-over plate 75 having an upper plate portion 76 and a 30 lower plate 77, which form the intermediate slot 78. The plates are provided with the corresponding openings 79 receiving the screw 80 which fits into the top of the sash 21. The upper plate is provided at one forward corner with the 35 downwardly projecting tit 81.

In this construction the upper end of the strip 35 is slit merely to form the bent-over angle members 82 and 83, which as indicated in Fig. 7, fit into the slots 78 on either side of the tit 81 40 and the screw 80. This arrangement permits an automatic adjustment of the weather strip 35' to accommodate relative expansion or contraction of the window frame 10 and sash frames 18 and 19.

45 It is apparent, of course, that many changes and modifications might be made in the structure shown, and that the end construction shown in Figs. 5, 6, 7 and 8 may be modified or arranged in different combinations and it is intended to 50 cover all such modifications or alterations as come within the scope of the appended claims.

Having thus described my invention what I 55 claim as new and desire to secure by Letters Patent is:

1. A weather stripping for connection to the edges of sashes to be placed in window frame constructions, said weather stripping being formed of sheet metal stampings, in the form of elongated strips, the sides of which are angularly bent in respect to each other, and the ends of which strips are provided with slots, whereby said strips may be automatically adjustably fitted upon the window sash constructions.

2. In combination with a sash, a weather 60 stripping comprising acutely angularly disposed side portions, which side portions are slit from each other so as to form fingers, said fingers being slotted, and when bent being adapted to overlay one another so said slots will register, 65 and means to connect said fingers to said sashes.

3. In combination, a channeled window frame, a sliding sash received in the channel of said window frame, and weather stripping carried by the sash fitted in the portion of said sash frame 75

received in said channel, said weather stripping consisting of an elongated angular strip of sheet metal, the angle between the sides of which are more acute than the edge of the sash, whereby 5 a resilient seal is had between the edge of the sash and the channel of the window frame, the end of said weather stripping being slotted to enable connection to said sash.

4. In combination, a channeled window frame, 10 a sliding sash received in the said window frame, and weather stripping carried by the sash, said weather stripping consisting of an elongated angular strip of sheet metal, the angle between the sides of which are more acute than the edge 15 of the sash to which it is attached, whereby a resilient seal is had, the attachment of said stripping to said sash being formed by providing a bent-over metal plate at one edge of the sash and by slotting the end of the strip to form two 20 tongues to be inserted into the slot between the upper and lower sides of said plate.

5. In combination, a channeled window frame, 25 a sliding sash received in the said window frame, and weather stripping carried by the sash, said weather stripping consisting of an elongated

angular strip of sheet metal, the angle between the sides of which are more acute than the edge of the sash to which it is attached, whereby a resilient seal is had, the attachment of said stripping to said sash being formed by splitting the stripping and slotting and bending over the fingers formed by the splitting so that the slots will register and receive a screw or nail. 5

6. In combination, a channeled window frame, 10 a sliding sash received in the said window frame, and weather stripping carried by the sash, said weather stripping consisting of an elongated angular strip of sheet metal, the angle between the sides of which are more acute than the edge 15 of the sash to which it is attached, whereby a resilient seal is had, the attachment of said stripping to said sash being formed by providing slots in the ends of the stripping to receive screws or nails for attachment to the sash. 15

7. In a weather stripping for a window sash 20 construction, an acutely angled metal strip fitted upon the less acutely angled edge of the sash, the ends of said strip having a slotted connection to the sash to enable automatic adjustment thereof. 25
